UNITED STATES PATENT OFFICE.

TEMPEST BOLDY, OF BRADFORD, ENGLAND.

DRYING MACHINE.

Application filed June 29, 1925, Serial No. 40,296, and in Great Britain March 5, 1925.

This invention relates to a drying machine that is primarily intended for drying wool in the form of sliver but may also be used for drying yarn in the hank form or for drying other textile material in an unfinished or finished condition, and to that type of drying machine in which the material to be dried is carried through a chamber by a series of endless open-work conveyors arranged one above the other, each upper conveyor being adapted to discharge its load upon the one next below it.

The chief object of the present invention is to introduce an improved air circulating system which will cause hot air to circulate either through the material on the conveyors; or if such material is in a heavy inseparable condition as occurs frequently in the case of wool slivers, to circulate between the superposed conveyors, exert an increased drying action on the slivers thereon, keep the whole of the interior of the casing in a heated condition and particularly the bottom or delivery end where the slivers issue from the casing. A further object of the invention is to cause the material to be guided efficiently in its passage from one conveyor to another so that it can be fed in wet at one end of the machine and passed out dry at the other end without any attention being required on the part of the attendant and without there being any risk of broken ends or other damage to the sliver during its passage through the machine.

According to this invention hot air is delivered from a heater to a casing through a conduit or pipe which is connected with the casing by branch pipes which enter the latter at different levels and extend wholly or partly across it, each branch pipe being formed with an aperture for directing the current of hot air in a longitudinal direction in relation to the conveyors the said current being regulated by a slide or other controlling device. The fan and heater may be arranged on the top of the machine and the bottom of the conduit or pipe may enter the casing at one side near the bottom and be formed with two apertures either or both of which may be independently controllable from the exterior of the casing. One of these apertures causes the hot air to pass along the underside of the bottom conveyor from the feed end of the casing to the delivery end and the other aperture causes the hot air to pass directly up the casing

at the feed end and also to circulate in a zig-zag fashion between the superposed conveyors when the latter are closed in by slivers or other material through which the hot air cannot pass.

In the accompanying drawings:—

Fig. 1 is a side elevation of a drying machine constructed according to this invention. 65

Fig. 2 is a plan of the machine shown in Fig. 1 with the fan and heater removed.

Fig. 3 is an end view of the drying machine, and

Figs. 4 and 5 are detached views showing one of the branch pipes drawn to a larger scale. 70

A indicates the drying machine and B a portion of the delivery end of a wool back wash machine. 75

In the example shown the drying machine comprises a rectangular casing containing a number of superposed endless open work conveyors *a* mounted on drums *a*¹ and arranged in staggered relationship to one another as shown. The endless open-work conveyors are advantageously constructed of wires which extend from one side of the machine to the other and are connected together at intervals by stranded wires which are woven in and out between the transversely arranged wires. The drums *a*¹ are provided at one end of the machine with sprocket wheels *a*² driven from a chain *a*³ which is driven by another chain *a*⁴ 80

through the intervention of change gearing *a*⁵ the chain *a*⁴ in the example shown being driven from a sprocket wheel *b* on the back wash machine B. Intermediate portions of the conveyor may be supported on rollers which take up slack and keep the conveyors in position and guides *a*⁶ are introduced to guide the sliver from one conveyor to another. Situated on the top of the casing is a fan C which blows air through a heater D. Extending from the latter is a conduit or pipe *d* which extends down one side of the casing and enters the latter near the bottom as shown in Fig. 3. The end of the conduit terminates in an elbow *d*¹ Fig. 2 100

and is formed with spaced openings *d*² (Fig. 3) adapted to be covered and uncovered by a slideable plate *d*³ (Fig. 2) which has similar openings and can be actuated from the exterior of the casing. The top of the elbow is formed with an aperture *d*⁴ through which a portion of the hot air can pass di- 105

- rectly up the casing at the feed end and also circulate in a zig-zag fashion between the superposed conveyors. This aperture may be controlled by a plate which can be moved from the exterior of the casing. The pipe or conduit d is connected with the casing by branch pipes d^5 (Figs. 3 and 4) which are formed with apertures d^6 and controlled by slides d^7 or other controlling devices. In the apertures d^6 are series of deflecting plates d^8 which are constructed as shown in Figs. 4 and 5 to distribute the current of hot air evenly from one side of the casing to the other and cause it to travel longitudinally in relation to the conveyors. Thus, each branch pipe has an elongated longitudinal aperture in which is disposed a series of longitudinally spaced deflectors or deflecting plates, which divide the aperture, and said deflectors extend gradually increasing distances into the pipe according to the direction of the flow of air in the pipe. The used air after passing through the casing escapes to the atmosphere through one or more valve controlled outlets d^9 .

What I claim as my invention and desire to secure by Letters Patent in the United States is:—

3. In a drying machine in which the material to be dried is carried through a chamber by a series of endless openwork conveyors arranged one above the other, the combination of a heater situated on the top of the chamber, an air conduit connecting the heater with the chamber and entering the latter at one side near the bottom, the portion of the conduit which enters the chamber having an opening at the front and an opening at the top and means for regulating the size of said openings.
4. In a drying machine in which the ma-

terial to be dried is carried through a chamber by a series of endless openwork conveyors arranged one above the other, the combination of a heater situated on the top of the chamber, an air conduit connecting the heater with the chamber and entering the latter at one side near the bottom, the portion of the conduit which enters the chamber having an opening at the front and an opening at the top, means for regulating the size of said openings, branch pipes extending from the air conduit and entering the chamber at different levels, each branch pipe being formed with an aperture for directing the current of hot air in a longitudinal direction in relation to the conveyors.

5. In a drying machine in which the material to be dried is carried through a chamber by a series of endless openwork conveyors arranged one above the other, the combination of a heater situated on the top of the chamber, an air conduit connecting the heater with the chamber and entering the latter at one side near the bottom, the portion of the conduit which enters the chamber having an opening at the front and an opening at the top, means for regulating the size of said openings, branch pipes extending from the air conduit and entering the chamber at different levels, each branch pipe being formed with an aperture, a series of deflectors in each of said apertures extending gradually increasing distances into the corresponding branch pipe, and means for independently controlling the volume of hot air that can pass through each branch pipe.

6. In testimony whereof I affix my signature.

TEMPEST BOLDY.
